[57] **CLAIM**

The ornamental design for an archery crossbow stabilizer, as shown and described.

DESCRIPTION

FIG. 1 is a perspective view of an archery crossbow stabilizer in accordance with my design;

FIG. 2 is a front end view thereof; and,

FIG. 3 is a top plan view, the bottom plan view being a mirror image thereof;

FIG. 4 is an elevated side view of FIG. 3 rotated ninety degrees, the opposite side view being a mirror image thereof; and,

FIG. 5 is a rear end view thereof.
